WINDOW WASHING DEVICE

Lottie Prager, New York, N. Y.

Application June 5, 1946, Serial No. 674,602

9 Claims. (Cl. 15—121)

1

This invention relates to window washing devices and in particular to one that can be used to clean the outside of the windows from inside the room.

An object of the invention is to provide a cloth and squeegee holding strip which may be adjusted to use either the cloth or the squeegee strip against the surface of the window.

A still further object of the invention is to provide a window cleaning device employing the lazy tong lever principle, the handle of which will be so arranged that the device will be manipulated for vertical reciprocating movement and may also be forced with lateral pressure against the outside surface of the window-pane at the same time that the handles are operated to impart said reciprocating motion.

A still further object of the invention is to provide a structure for holding the wiping cloth and squeegee strip that will employ clamping members to hold a felt pad and a rubber strip in place and which will be of such compact construction that it can be readily operated between the upper and lower sashes of a window.

Still further objects of the invention include a lazy tong arrangement of levers that is simple in construction, light in weight, and upon which may be mounted, so that there is no lateral tilting movement thereof, a wiping strip which may be adjusted to bring either a cloth edge or a rubber edge against the pane of glass; one which can be readily used by women; can be made in different lengths for cleaning high windows or walls and one which is particularly adapted to household use.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a view in perspective of the parts of a window showing the use therewith of the window cleaning device constructed in accordance with the present invention.

Fig. 2 is a fragmentary view in elevation taken through the upper and lower sash members of a window structure, showing the application thereto of the improved window cleaning device.

Fig. 3 is an enlarged plan view of the wiping strip carrier that is mounted on top of the implement, an adjustable position thereof being illustrated in outline.

Fig. 4 is a view in side elevation of the strip illustrated in Fig. 3.

Fig. 5 is an enlarged vertical sectional view taken on the line 5—5 of Fig. 3, illustrating the

2

clamp arrangement used in connection with the strip.

Fig. 6 is an enlarged vertical sectional view taken on the line 6—6 of Fig. 3, showing the 5 detent means employed in holding the wiping strip in either of its adjusted positions.

Fig. 7 is a top plan view, similar to Fig. 3, of a modified form of strip structure in which clamp arms are employed to hold the fabric and rubber 10 wiping strips.

Fig. 8 an enlarged section on the line 8—8 of Fig. 7, showing the shape of the arms and the rods coacting therewith.

Fig. 9 is an enlarged vertical sectional view 15 taken on the line 9—9 of Fig. 7, showing the arrangement of the detent means and the mounting of the clamp arms on the strip.

Fig. 10 is a fragmentary view in perspective at one end of one of the arms of the strip member 20 illustrating the method of opening a clamp rod.

Referring to the drawings in detail, 10 indicates a window casement in which a lower sash 11 and an upper sash 12 are slidably mounted in the usual manner, the outer surfaces of the 25 panes of glass 13 which are to be cleaned without the necessity of leaning out the window. My improved appliance for cleaning windows from the inside consists of a lazy tong lever arrangement 14 consisting of diagonally disposed levers 30 15 and 16 pivoted to each other as at 17 for scissor-like action and pinned to each other at their extremities as at 18 to provide the necessary extension and collapsing action necessary to vertically reciprocate the wiping head structure 19 mounted at the upper end thereof. The lower end of the lever arrangement has secured thereto the handles 20 which are shaped to provide horizontally extending portions 21 and upwardly curved vertical portions 22 the latter 35 of which are disposed inside the window and provide hand grips for the person manipulating the cleaning implement.

It will be noted in Fig. 2 that the horizontally extending portions 21 of the handles 20 may 45 rest on the sash frame or window sill and have sliding movement thereon as the device is manipulated vertically, the person operating the device being able to swing the handles inwardly in order to bring the wiping head 19 forcibly 50 against the window.

The wiping head 19 consists of parallel arms 25 secured together at their ends by cross pieces 26 and by an intermediate bridging piece 27. The cross pieces 26 are each shaped to provide 55 a vertical portion 28 and a finger blade 29 with which the fingers of the operator may engage when clamp members 30 are manipulated to attach or release a wiping cloth 31 or a rubber squeegee strip 32 about the longitudinal edges 60 of the arms 25.

The clamps 30 are pivoted as at 33 to the vertical portions 28 and are normally urged to clamping position by the springs 34. A pair of these clamps are provided on the upper and under surfaces of the outer ends of the wiping head 19. It is evident that, by manipulation of the clamps 30, the fabric washing strip and rubber squeegee strip may be replaced or reversed when necessary with a minimum of adjustment of the parts of the device.

In order to eliminate the necessity of taking the fabric strip out of the wiper and inserting the rubber squeegee strip, the wiping head 19 is pivoted on the threaded stud 35 between the washer 36 and a nut 37, the upper end of the stud 35 having secured thereto a square block 38, the opposite corners of which are arranged to be engaged by the spring detent strips 39 secured as at 40^a to the bridging piece 21. The lower end of the stud 35 is shaped to provide a flattened portion 40 to the opposite sides of which the upper ends of the upper lazy tong levers are pivoted as at 41. This flattened portion 40 of the wiping strip carrier prevents the head 19 from pivoting laterally or from having a longitudinal teetering action, the flat portion 40 thus holding the wiping strip firmly against the pane of glass in either of the adjusted positions of said wiper. As illustrated in Fig. 3, in dot and dash lines, the wiping head 19 may be rotated to bring either the cloth cleaning member 31 or the squeegee strip 32 against the window pane.

In the Figs. 7-10, inclusive, a slightly modified form of structure is shown which provides for a wiping head 50 having arms 51 at the opposite sides and ends thereof which are arcuately shaped to receive in clamping contact cylindrically shaped rods 52 pivoted as at 53 to the inside of the bridge centerpiece 54 from which the arms 51 extend.

This bridging piece 54 is mounted on a threaded stud 55 between a nut 56 and a squared block 57, the latter of which is secured to the upper end of the stud 55. The head 50 is thus mounted for rotation and is held in either of its adjusted positions by the spring detent strips 58 and 59 which are secured to the member 54 in any suitable manner.

The rods 52 are forced to seat in the arms 51 by springs 60 positioned between said rods 52 on guide pins 61 at a point adjacent the pivots 53. It is evident that, by manual manipulation of any of the rods 52 against the yielding action of the springs 60, the fabric 62 or the rubber squeegee strip 63 may be replaced. To assist in the manual operation of the rods 52, the outer ends thereof may be provided with the finger pins 65 which may be engaged by the finger of the operator to swing the rods 52 open for the insertion of the rubber or cloth members.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a window washing device having a vertical lazy tong structure for extension along the outer surface of a window pane and terminating at its top end in a vertical stud, a horizontal pair of spaced parallel arms one for supporting a

wiping cloth and the other for supporting a rubber squeegee, a bridging piece connecting said arms intermediate of their ends and formed with an opening through which the stud rotatively extends, means retaining said bridging piece rotatively in position on said stud, and means for holding said bridging piece in turned positions on said stud with either of said arms engaging the window pane, said holding means comprising a square block mounted on said stud above said bridging piece, said square block being mounted on said stud with a line extending through a pair of opposed corners extended parallel to said arms when one thereof engages the window pane, and spring detent strips mounted at their one ends on said bridging piece and having their free ends engaging and gripping said opposed corners.

2. In a window washing device having a vertical lazy tong structure for extension along the outer surface of a window pane and terminating at its top end in a vertical stud, a horizontal pair of spaced parallel arms one for supporting a wiping cloth and the other for supporting a rubber squeegee, a bridging piece connecting said arms intermediate of their ends and formed with an opening through which the stud rotatively extends, means retaining said bridging piece rotatively in position on said stud, and means for holding said bridging piece in turned positions on said stud with either of said arms engaging the window pane, said holding means comprising a square block mounted on said stud above said bridging piece, said square block being mounted on said stud with a line extending through a pair of opposed corners extended parallel to said arms when one thereof engages the window pane, and spring detent strips mounted at their one ends on said bridging piece and having their free ends engaging and gripping said opposed corners.

3. In a window washing device having a vertical lazy tong structure for extension along the outer surface of a window pane and terminating in a vertical stud, a wiping head mounted on the stud and comprising in combination a horizontal pair of spaced parallel arms, one for supporting a wiping cloth and the other for supporting a rubber squeegee, means for clamping a wiping cloth and a rubber squeegee in position on said arms, a bridging piece connecting said arms intermediate of their ends and formed with an opening through which the stud rotatively extends, means retaining said bridging piece rotatively in position on said stud, and means for holding said wiping head in position on said stud with either of its two arms engaging the window pane, said holding means comprising a square block mounted on said stud above said bridging piece, said square block being mounted on said stud with a line extending through a pair of opposed corners extended parallel to said arms when one thereof engages the window pane, and spring detent strips mounted at their one ends on said bridging piece and having their free ends engaging said opposed corners.

4. In a window washing device having a vertical lazy tong structure for extension along the outer surface of a window pane and terminating in a vertical stud, a wiping head mounted on the stud, comprising a horizontal pair of spaced parallel arms, one for supporting a wiping cloth and the other for supporting a rubber squeegee,

means for clamping a wiping cloth and a rubber squeegee in position on said arms, a bridging piece connecting said arms intermediate of their ends, said arms being arcuately curved in a direction away from each other forming concaved inner faces, said clamping means comprising cylindrical clamp rods pivotally attached to said bridging piece and extended in opposite directions therefrom between said arms for clamping a wiping cloth and a rubber squeegee against said concaved inner faces of said arms, resilient means urging said rods into engagement with the inner faces of said arms, and means at the outer ends of said rods for facilitating manual pivoting of said rods away from said arms against the action of said resilient means.

5. In a window washing device having a vertical lazy tong structure for extension along the outer surface of a window pane and terminating in a vertical stud, a wiping head mounted on the stud, comprising a horizontal pair of spaced parallel arms, one for supporting a wiping cloth and the other for supporting a rubber squeegee, means for clamping a wiping cloth and a rubber squeegee in position on said arms, a bridging piece connecting said arms intermediate of their ends, said arms being arcuately curved in a direction away from each other forming concaved inner faces, said clamping means comprising cylindrical clamp rods pivotally attached to said bridging piece and extended in opposite directions therefrom between said arms for clamping a wiping cloth and a rubber squeegee against said concaved inner faces of said arms, resilient means urging said rods into engagement with the inner faces of said arms, and means at the outer ends of said rods for facilitating manual pivoting of said rods away from said arms against the action of said resilient means, said resilient means comprising aligned pairs of pins extended toward each other from opposed pairs of said rods adjacent their pivots, and expansion springs extended between said aligned pairs of pins.

6. In a window washing device having a vertical lazy tong structure for extension along the outer surface of a window pane and terminating in a vertical stud, a wiping head mounted on the stud, comprising a horizontal pair of spaced parallel arms, one for supporting a wiping cloth and the other for supporting a rubber squeegee, means for clamping a wiping cloth and a rubber squeegee in position on said arms, a bridging piece connecting said arms intermediate of their ends, said arms being arcuately curved in a direction away from each other forming concaved inner faces, said clamping means comprising cylindrical clamp rods pivotally attached to said bridging piece and extended in opposite directions therefrom between said arms for clamping a wiping cloth and a rubber squeegee against said concaved inner faces of said arms, resilient means urging

said rods into engagement with the inner faces of said arms, and means at the outer ends of said rods for facilitating manual pivoting of said rods away from said arms against the action of said resilient means, said means for facilitating manual pivoting comprising finger pins extended vertically from the outer ends of said rods to be conveniently gripped.

7. In a window washing device as claimed in claim 1 wherein cross pieces are extended between the outer ends of said parallel arms on opposite sides of said bridging piece, and clips mounted on said cross pieces to engage the wiping cloth and the rubber squeegee for retaining them in position on said parallel arms.

8. In a window washing device as claimed in claim 1 wherein cross pieces are extended between the outer ends of said parallel arms on opposite sides of said bridging piece, and clips mounted on said cross pieces to engage the wiping cloth and the rubber squeegee for retaining them in position on said parallel arms, said cross pieces having oppositely extended vertical portions, said vertical portions between said parallel arms and at right angles to said parallel arms, said clips being pivotally mounted on said vertical portions to bear against the top and bottom faces of said parallel arms.

9. In a window washing device as claimed in claim 1 wherein cross pieces are extended between the outer ends of said parallel arms on opposite sides of said bridging piece, and clips mounted on said cross pieces to engage the wiping cloth and the rubber squeegee for retaining them in position on said parallel arms, said cross pieces having oppositely extended vertical portions, said vertical portions between said parallel arms and at right angles to said parallel arms, said clips being pivotally mounted on said vertical portions to bear against the top and bottom faces of said parallel arms, and resilient means urging said clips into their operative positions engaged with said parallel arms.

LOTTIE PRAGER.
